[57] CLAIM

The ornamental design for seat, as shown and described.

DESCRIPTION

FIG. 1 is a top right perspective view of a seat showing my ornamental design thereof in the form of a chair.

FIG. 2 is a bottom left perspective view thereof.

FIG. 3 is a top right perspective view of my design for a seat shown as a love seat.

FIG. 4 is a top right perspective view of the design of a seat shown as a sofa.

FIG. 5 is an enlarged view of the seat of FIG. 1 taken generally from circle 5 of FIG. 1.

FIG. 6 is an enlarged view of the seat of FIG. 1 taken generally from circle 6 of FIG. 1.
